UNITED STATES PATENT OFFICE

155,607

DESIGN FOR AN AUTOMOBILE GRILLE
GUARD

Laurence C. Helms, Travis R. Helms, and George Tungett, Grand Rapids, Mich., assignors to Helms Industrial Development Company, Grand Rapids, Mich., a corporation of Michigan

Application September 29, 1947, Serial No. 141,628

Term of patent 14 years

(Cl. D14—6)

To all whom it may concern:

Be it known that we, Laurence C. Helms, Travis R. Helms, and George Tungett, citizens of the United States, residing at Grand Rapids, in the county of Kent and State of Michigan, have invented a new, original, and ornamental Design for an Automobile Grille Guard, of which the following is a specification, reference being had to the accompanying drawing, forming part thereof.

Fig. 1 is a front angular perspective view of an automobile grille guard showing the new design.

Fig. 2 is a front elevation of the same, and

Fig. 3 is a plan view of the same.

We claim:

The ornamental design for an automobile grille guard, substantially as shown.

LAURENCE C. HELMS.
TRAVIS R. HELMS.
GEORGE TUNGETT.
